UNITED STATES PATENT OFFICE

PETER H. MEYER, OF BUFFALO, NEW YORK

DESIGN FOR A NOSE-BRIDGE MOUNTING FOR SPECTACLES

Application filed March 12, 1930. Serial No. 34,836. Term of patent 14 years.

To all whom it may concern:

Be it known that I, PETER H. MEYER, a citizen of the United States, residing at Buffalo, in the county of Erie and State of New York, have invented a new, original, and ornamental Design for a Nose-Bridge Mounting for Spectacles, of which the following is a specification, reference being had to the accompanying drawing, forming a part thereof.

The figure is a perspective view of a nose bridge mounting for spectacles showing my new design.

I claim:

The ornamental design for a nose bridge mounting for spectacles, as shown.

PETER H. MEYER.
